(57) **CLAIM**

The ornamental design for a bag, as shown and described.

DESCRIPTION

The nature of the article in which the design is embodied is a baseball-cap-shaped bag.

FIG. 1 is a top plan view of a bag showing my new design, shown in an open condition;

FIG. 2 is a right side view thereof;

FIG. 3 is a left side view thereof; and,

FIG. 4 is a bottom plan view thereof.

The broken lines are understood to represent stitching.
